UNITED STATES PATENT OFFICE.

NELSON D. CLARK, OF CHICAGO, ILLINOIS, ASSIGNOR TO UNION SPECIAL MACHINE COMPANY, OF CHICAGO, ILLINOIS, A CORPORATION OF ILLINOIS.

OVERSEAMING-MACHINE.

1,324,541.

Specification of Letters Patent.

Patented Dec. 9, 1919.

Application filed November 21, 1916. Serial No. 132,668.

To all whom it may concern:

Be it known that I, NELSON D. CLARK, a citizen of the United States, residing at Chicago, in the county of Cook, State of Illinois, have invented certain new and useful Improvements in Overseaming-Machines, of which the following is a description, reference being had to the accompanying drawings, and to the figures of reference 10 marked thereon.

The invention relates to new and useful improvements in overseaming sewing machines and more particularly to the manner of supporting the stitch finger around 15 which the threads are laid by the stitch forming mechanism.

An object of the invention is to provide a sewing machine of the above character with the stitch finger which is located beneath the material being stitched and which is supported independently of the throat plate or work support on which the material rests while it is being stitched.

A further object of the invention is to 25 provide a combined means for supporting the throat plate and the stitch finger, said stitch finger being supported independently of the throat plate.

A still further object of the invention is 30 to provide combined means for supporting the throat plate and the stitch finger and also a needle guard or loop deflector.

These and other objects will in part be 35 obvious and will in part be hereinafter more fully disclosed.

In the drawings, which show by way of illustration of the invention:—

Figure 1 is a view partly in section and 40 partly in front elevation showing a portion of a sewing machine having my improvements applied thereto;

Fig. 2 is a vertical sectional view through 45 the overhanging arm adjacent the needle head and looking toward the needle head;

Fig. 3 is a plan view showing the throat plate, the work support, the stitch finger and the stitch forming elements;

Fig. 4 is a perspective view of the stitch finger, the loop deflector and the means for 50 supporting the same at the throat plate;

Fig. 5 is a similar view but showing the parts separated and the section of the bed plate omitted; and

Fig. 6 is a detail showing the upper end 55 of the supporting post, the stitch finger car-

ried thereby and the loop deflector carried by the post.

Prior to my invention it had been common to provide a throat plate carrying a stitch finger located beneath the material 60 and around which the threads are interlocked. It sometimes occurs that the needle hole is improperly positioned relative to the needle when the throat plate is initially secured in place, thus necessitating the 65 proper shifting of the cloth plate to which the throat plate is attached and consequently positioning the stitch finger out of its proper relation to the needle. The stitch finger may be formed integral with the 70 throat plate or may be attached thereto. In the latter case, the attaching surface of the plate is so small, on account of the feed slots that the attaching shank of the finger must also be small. It also sometimes happens that the stitch finger becomes broken, 75 requiring either an entirely new throat plate or a new stitch finger. One of the purposes of the present invention is to provide a rigid support for the stitch finger which is 80 independent of the throat plate and work support, so that the stitch finger may be adjusted or removed and replaced at will.

The sewing machine to which the invention is applied is the ordinary overseaming 85 machine in which a needle penetrates the fabric while complementary stitch forming devices carry the needle loops or other thread loops around the edge of the material to a position where the needle enters 90 said loop, and a stitch finger is located beneath the material and these thread loops are laid around the stitch finger. The stitch finger is entirely independent of the throat plate, said throat plate being cut 95 away to form a space for the stitch finger so that the upper face of the stitch finger is substantially flush with the upper surface of the throat plate.

Mounted on the bed, beneath the work 100 support is a supporting post which extends upwardly from the bed and engages the throat plate at the under face thereof adjacent the needle opening and serves as a means for supporting the throat plate. The 105 stitch finger is adjustably attached to this supporting post so that it may be adjusted or entirely removed from the post and a new stitch finger substituted therefor. A loop deflector is also carried by the post 110

which coöperates with the needle in insuring that the loop of needle thread is thrown out properly for the entrance of the coöperating looper.

Referring more in detail to the drawings, I have shown my invention as applied to a sewing machine consisting of a supporting bed 1, which carries an overhanging arm 2 in which a needle bar 3 reciprocates. This 10 needle bar is reciprocated by a needle lever 5 which is connected to the needle bar by a link 6. Mounted on the supporting bed is a work support 7 which is provided with a throat plate 8. Said throat plate is formed 15 with a needle opening 9 and slots for the feed dog 10. The throat plate is secured to the cloth plate by suitable screws 11.

Coöperating with the needle beneath the work support, as shown in the drawings, is 20 a looper 12 which may be a thread carrying looper, and coöperating with this thread carrying looper 12 and also with the needle above the work support is a second looper 13. These loopers operate to enchain their 25 thread loops with the needle thread loops, which enchained loops extend around the edge of the material. The material, as it is fed to the stitching mechanism, may be trimmed by suitable trimming blades, which 30 are indicated at 14 in the drawings. The enchained thread loops are formed around a stitch finger, indicated at 15 in the drawings. The stitch finger operates in the manner well known in the art, to support the 35 thread loops as the stitches are being set and the loops are finally fed off from the end of the stitch finger. Located beneath the work support is a stitch finger supporting post consisting of a sleeve 16 and a supporting rod 17 to which said sleeve is secured 40 by means of a clamping screw 18, which extends through a split collar 19 formed integral with the sleeve 16. The rod 17 is threaded at its lower end, as indicated at 20, and 45 this threaded end of the rod engages a threaded socket in the bed plate 1. The rod, at its lower end, is formed with a groove 21, adapted to receive a screw driver, that the rod may be readily turned for adjusting the 50 height of the sleeve which is supported thereby. A set screw 22 serves as a means for locking the rod against movement when it is brought to the desired position. A set screw 23 serves to hold the rod and the sleeve 16 55 in a predetermined adjusted position.

The sleeve 16 is made in two sections. The lower section 24 carries the split collar 19 and is clamped to the post. The upper section 25 is adjustably attached to the lower 60 section 24. Said lower section 24 has a groove 26 in its upper end while the section 25 is formed with a lateral shank 27 adapted to fit in the groove 26. Said shank 27 is formed with a slot 28 adapted to receive a 65 screw 29. The slot 28 is elongated so that

the upper section 25 may be adjusted transversely of the lower section 24 and held in adjusted positions by the screw 29. The upper section 25 of the supporting sleeve is provided with a groove 30 in its upper end. The stitch finger 15 has a laterally extending shank 31 which fits in the groove 30 and this shank is provided with an elongated slot 32 adapted to receive a screw 33 which extends into the section 25 of the sleeve and clamps the stitch finger thereto. Secured to the side of the section 25 is a plate 34 which is provided with a flat upper end 35 and also a vertical groove 36. Said plate is also provided with an elongated vertical slot 37 adapted to receive a screw 38, which is threaded into the section 25. The throat plate has a recess in which the stitch finger is located and said stitch finger forms one wall of the needle opening 9.

The stitch finger is capable of several adjustments, one through the lateral adjustment of the section 25 of the sleeve, another through the adjustment of the stitch finger itself on the sleeve and still another through the angular adjustment of the sleeve 16 around the rod 17 and still another by adjusting the vertical position of the rod 17 in the supporting bed or adjusting the sleeve vertically on the rod. Through these adjustments the stitch finger may be readily placed so as to properly coöperate with the needle and the loopers.

The plate 34 is also adjusted so as to engage the under face of the throat plate and support the same by the flat upper end 35 at the point adjacent the needle. This firmly supports the throat plate against the downward thrust of the presser foot when the feed dog drops. The vertical groove in this 100 plate receives the needle and not only holds the needle in its proper path but also causes the needle to throw out its thread loop so that the looper may enter the same.

From the above description it will be apparent that I have provided a supporting post which supports the throat plate from the bed plate of the machine, and I have also provided means for rigidly supporting a stitch finger beneath the material, entirely 105 independently of the throat plate or the work support. This finger is also supported in a manner whereby it may be adjusted to properly position the same.

Having thus described the invention, what 110 is claimed as new is:—

1. An overseaming machine including in combination, a work support having a throat plate, a stitch finger located beneath the material, and means beneath the work support 115 for supporting said stitch finger in a fixed position independently of said work support and the throat plate.

2. An overseaming machine including in combination, a work support having a 120

throat plate provided with a cutaway portion, a stitch finger located in the cut away portion of the throat plate, and means beneath the work support and independent of the throat plate for supporting said stitch finger in a fixed position.

3. An overseaming machine including in combination, a work support having a throat plate provided with a cut away portion, a 10 stitch finger located in said cut away portion and having its upper face substantially flush with the upper face of the throat plate, and means independent of the throat plate for supporting said stitch finger.

15 4. An overseaming machine including in combination, a needle, a work support having a throat plate, a stitch finger, and means independent of said work support and the throat plate for supporting said stitch finger, said means being adjustable transversely of the line of stitching whereby the operative position of said stitch finger may be shifted laterally.

20 5. An overseaming machine including in combination, a needle, a throat plate having a needle opening and a cut away portion, a stitch finger located in the cut away portion and forming one side of the needle opening, and means independent of the 25 throat plate for supporting said stitch finger.

30 6. An overseaming machine including in combination, a supporting bed, a work support, a throat plate carried thereby, a stitch finger supported by the bed independently 35 of the work support and located with its upper face substantially flush with the upper face of the throat plate.

7. An overseaming machine including in 40 combination, a supporting bed, a work support carried by said supporting bed and having a throat plate, a supporting post carried by the bed and supporting said throat plate, and a stitch finger separate from said throat plate and carried by said supporting post.

45 8. An overseaming machine including in

combination, a supporting bed, a work support carried by said supporting bed and having a throat plate, a supporting post carried by the bed and supporting said throat plate, 50 a stitch finger, and means for adjustably attaching said stitch finger to said supporting post whereby the stitch finger may be adjusted and supported with its upper face substantially flush with the upper face of the 55 throat plate.

9. An overseaming machine including in combination, a needle, a supporting bed, a work support having a throat plate, a post mounted on the bed and supporting said 60 throat plate, a stitch finger carried by said supporting post, and a loop deflector carried by said supporting post and coöperating with said needle.

10. An overseaming machine including in 65 combination, a supporting bed, a throat plate, a supporting post comprising a supporting rod, a sectional sleeve carried thereby, a stitch finger carried by said supporting post and having its upper face substantially flush with the upper face of the 70 throat plate.

11. An overseaming machine including in combination a supporting bed, a throat plate, a supporting post carried by said bed 75 and comprising a supporting rod, a sleeve adjustable vertically on said rod, said sleeve having two sections one of which is laterally adjustable relative to the other, a stitch finger carried by the sleeve and adjustable laterally thereof, said throat plate having a cut away portion for said stitch finger whereby said stitch finger may be positioned with its upper face substantially flush with the upper 80 face of the throat plate.

85 In testimony whereof I affix my signature in the presence of two witnesses.
